(No Model.)

L. W. POND.

METAL PLANING MACHINE.

No. 351,937.

Patented Nov. 2, 1886.

Rufus B. Dovalen
N. C. Steere

Lucius W. Pond

UNITED STATES PATENT OFFICE.

LUCIUS W. POND, OF WORCESTER, MASSACHUSETTS.

METAL-PLANING MACHINE.

SPECIFICATION forming part of Letters Patent No. 351,937, dated November 2, 1886.

Application filed January 26, 1886. Serial No. 189,803. (No model.)

To all whom it may concern:

Be known that I, LUCIUS W. POND, a citizen of the United States, residing at Worcester, in the county of Worcester and State of Massachusetts, have invented certain new and useful Improvements in Metal-Planing Machines, of which the following is a specification, accompanied by drawings which illustrate a metal-planing machine embodying my invention, and in which—

Figure 1 is a side elevation; Fig. 2, a plan view, partly in section. Fig. 3 is a detached view of a portion of the belt-shifting mechanism. Fig. 4 is a front elevation of the same; and Fig. 5 is an end view of the bed.

Similar letters refer to similar parts in the several views.

My invention consists in providing facilities for operating upon work of too great length to pass between the upright frame of the planing-machine by means of a throat or overhanging head; in providing a sliding cover, sliding in grooves in the inner side of the ways, for the purpose of protecting the shipping mechanism; in the use of independent shipping devices for each of the driving-belts, whereby the time at which the driving-belts are shifted relatively to each other can be changed to suit the varying conditions of the belts; and in certain details of construction and operation, as hereinafter described, and specifically set forth in the claims.

A denotes the bed; B, the reciprocating table, moving on the ways *a a'*; C, the upright sides supporting the head; D D², the driving-pulleys; D' D², the loose pulleys; E E', sliding rods, each carrying at its outer end the belt-eyes *b b'*, inclosing the driving-belts 1 and 2, moving in opposite directions.

F is a bell-crank lever pivoted upon the upper side of the plate *c*, attached to the inside of the bed A, and having the arm *d* pivoted to the sliding belt-rod E, and the arm *d'* attached, by the connecting-rod *f*, with the shipping devices hereinafter described. Similarly, the bell-crank F' is pivoted on the under side of the plate *c*, with one of its arms, *e*, pivoted to the sliding belt-rod E' and the other arm, *e'*, connected with the shipping devices by the connecting-rod *f'*.

Journalled in the side of the bed is the sleeve

G, carrying at its outer end the arm G' and at its inner end the arm G², to which the connecting-rod *f'* is pivoted.

Within the sleeve G is journaled the shaft H, having at its outer end an arm, H', and at its inner end the arm H², to which the connecting-rod *f* is pivoted. To the side of the table T attach the dog I, adjustable along the side of the table, and having an adjusting-screw, *i*, arranged so that when the table moves to the left the screw will strike the spur *g* on the lever G', and dog I also has a spur, *i'*, projecting outwardly and downwardly and arranged to strike the edge of the arm H'. The position of the arms G' and H', at the beginning of the movement of the table to the left, is shown in Fig. 1. The screw *i* is adjusted to strike the spur *g* and move the arm G', and through its connected mechanism start the driving belt 1 from the pulley D in advance of the impact of the spur *i'* against the arm H', and consequent motion of the belt 2 from the loose pulley D² to fast pulley D'.

At the end of the return motion of the table just described, the positions of the arms G' H' are shown in Fig. 4, with the arm G' slightly in advance of the arm H', effecting the shifting of the belts and reversing the motion of the table.

A dog, J, is adjustably attached to the side of the table, said dog having a projecting finger, *j*, arranged to strike the spur *h* on the arm H' as the table moves to the right, and through the connected shipping mechanism move the belt 2 in advance of the contact of the adjusting-screw *j'* with the edge of the arm G' and consequent shifting of the belt 1 from the loose pulley D². As the spur *h* moves in an arc of a circle and the finger *j* in a straight line, the spur *h* will be carried past its highest vertical position, so the finger *j* will pass above it, allowing the arm H' to remain at rest until moved by the advancing screw *j'*, which is placed on the dog J in position to strike the edges of both the arms G' and H', bringing them together in the position shown in Fig. 1, effecting the shifting of the driving-belts, and again reversing the motion of the table.

I am aware that a mechanism has been used consisting of sliding rods carrying belt-eyes and actuated by a bell-crank operated by a vi-

brating arm, which is moved by dogs adjustable in position on the side of the table; but in such devices the motion of the belt-eyes is uniform, and the "lead" or advance made in shipping the driving-belt from off a tight pulley before shipping the oppositely - running belt upon a tight pulley is constant and unvarying through all the changing conditions of the belts, which, in modifying their tendencies to stick upon the pulleys, requires a variation in the lead of the driving-belt, which in my improved shipping mechanism can easily be secured by changing the adjusting-screws *i* and *j'*, and thereby varying the period between the contact of the screw *i* and spur *i'*, or between the finger *j* and screw *j'*. Neither do I claim, broadly, the use of mechanism by which the lead of the belts may be varied, as this has been accomplished in belt-shipping devices consisting of a single belt-actuating mechanism by changing the relative positions of the operating parts. In the belt shipping device forming the subject of my present invention I employ two distinct and independently acting mechanisms between the reciprocating table and the belts, whereby I am able to change the lead of the belts, as desired, by means of a change confined to the adjustable dogs attached to the reciprocating table and without any rearrangement of the shipping mechanism intervening between said dogs and the driving-belts.

It is frequently desirable to plane transversely across long pieces which will not pass between the upright sides *C*, and in such cases it has been customary to extend the cutting-tool farther out from the upright. I accomplish the same result and avoid the necessity of extending the cutting-tool forward, which has many disadvantages, by forming a throat, *K*, at the plane of the table-top, allowing the work which extends laterally beyond the sides *C* to pass beyond the cutting-tool. This throat may be formed in the sides themselves or by making an overhanging head.

Upon the inside of the ways *a a'*, as seen in Fig. 5, I form grooves *k k*, in which I slide a plate, *L*, forming a cover for the protection of the shipping or other mechanism which may be placed within the bed.

What I claim as my invention, and desire to secure by Letters Patent, is—

1. In a metal-planing machine, the combination, with a pair of rods provided with belt-eyes arranged to ship the driving-belts of the machine and adjustable dogs attached to the reciprocating table, of two independently-

acting operating mechanisms, each connected with one of said rods and arranged to be actuated by said dogs, substantially as described, and for the purpose set forth.

60

2. The combination, with a vibrating arm attached to a sleeve journaled in the bed and actuated by the reciprocating table, and a vibrating arm attached to a shaft journaled in said sleeve and actuated by the reciprocating table, of shipping mechanisms operating said rocking sleeve and shaft, whereby the driving-belts are shifted, as described, and for the purpose set forth.

3. The combination, in a metal - planing machine, with independently-acting belt-shipping mechanisms actuated by dogs attached to the reciprocating table, of adjusting-screws carried by said dogs, whereby the time of contact with said shipping mechanisms may be varied, as described, and for the purpose set forth.

4. The combination, with vibrating arms *G'* and *H'*, journaled in concentric bearings in the bed of the machine, the arm *G'* having a spur, *g*, and the arm *H'* having a spur, *h*, said arms having connected mechanism for actuating the belt-eyes and shipping the driving-belts, of dogs *I* and *J* adjustable on the reciprocating table, said dog *I* adapted to move the arm *G'*, and having a spur, *i*, adapted to move the arm *H'*, said dog *J* adapted to move the arm *G'* and having a finger adapted to move the arm *H'* in advance of the arm *G'*, as described, and for the purpose set forth.

5. In a metal-planing machine, the combination, with vibrating arms journaled in the bed of the machine and having connected belt-shipping mechanisms, substantially as described, of dogs adjustably attached to the reciprocating table and adapted to move said arms at different periods of time, as described, and for the purpose set forth.

6. In a metal-planing machine having two independently-acting belt-shipping mechanisms and actuating-dogs attached to the reciprocating table, the combination, with said dogs, of adjusting-screws whereby the relative movement of the belt-shipping mechanisms is varied, substantially as described.

7. In a metal-planing machine, the ways *a a'*, provided with grooves on their inner sides for the reception of a covering-plate, substantially as described.
